Inventor:
William H. Nichols
by Chas. F. Perkins Attorney

UNITED STATES PATENT OFFICE.

WILLIAM E. NICHOLS, OF BENNINGTON, VERMONT.

ELECTRICAL RECEPTACLE.

Application filed February 12, 1924. Serial No. 692,936.

My invention relates to electrical receptacles and has for its object the production of a gang one-piece electrical receptacle and plate for use in the wall of a building, in 5 dining tables and other household furniture, which may be set flush with the surface of the wall or furniture and is convenient and economical to apply. It is also adapted for use as a portable receptacle to be laid loosely 10 upon the desk or table or other convenient place.

In the accompanying drawing illustrating my invention Fig. 1 is a plan view without the service plug. Fig. 2 is a side elevation 15 with the service plug inserted. Fig. 3 is an end elevation with the attachment plug cap. Fig. 4 is a vertical section through the line X—X on Fig. 1. Fig. 5 is a vertical section through the line Y—Y on Fig. 2.

7 is a box rectangular in cross section, 20 designed for three gangs or outlets 13, 14 and 15, as illustrated. A convenient size of box for that number of gangs I find to be about five inches long and an inch wide. It is 25 clear that the box may be made longer or shorter, and the number of outlets may be more or less according to the needs of a particular installation, without departing from the essentials of the invention. 8 is a

30 plate about seven inches long made integral with the box, constituting a one-piece receptacle and plate. I prefer to make the receptacle of insulating material such as bakelite, wood fibre or hard rubber by moulding it in 35 a press in the usual way of working such materials, although I do not limit my invention thereto. It is obvious that it may be made of cast metal if the inserts are suitably insulated therefrom. 9, 9 are parallel electric conductors terminating at one end of the 40 receptacle with the inserts 10, 10 in the cylindrical recess 11. Contacting with the conductors 9, 9, and secured thereto by welding, soldering or in any suitable manner, are 45 the inserts 10, 10 for the service plug 12, and the inserts 16, in the gangs or outlets 13, 14 and 15. 21 is an attachment plug cap connected by its cord 18 to some electric device 50 for household use, such as a fan, cooking utensil or laundry machine. I have designed the particular three gang receptacle shown in the drawing for a dining or serving table with attachments for three electric fixtures, such, for instance, a percolator, a 55 toaster and a grill, to be simultaneously or

separately used. The receptacle is complete in itself and may be so inserted in an opening cut for the purpose in the side of the table, that the surface of the plate 8 may be flush with the wood work of the table, making thereby a neat and attractive appearance, and being conveniently located for the use of any or all of the said fixtures. When used as a portable receptacle for the table or desk it is, of course, unnecessary to provide 60 the flange 8 shown in the drawing. It is

obvious that the receptacle may be used for connection with any variety of electric fixtures, and as many as may be desired by providing a receptacle with the requisite number 65 of outlets. The female service plug 12 is designed to make contact with the male inserts 10, 10, and thereby energize the circuit of the receptacle. The service plug 12 is constructed in a form to protect the user 70 from an electric shock which might occur by accidentally coming in contact with the terminals if they were exposed. The terminals 23 are concealed in the slots 19, 19, of the service plug 12, and are connected with an 75 electric cord provided with a plug adapted to take the current from the house fixtures 80 in the usual manner.

20 is one of the attachment plugs provided 85 with a cap 21 and a cord 18 to connect with any electric device to be operated by the receptacle. The attachment plug 20 is adapted to form contact with any of the inserts 16, and thereby to take the current 90 from the conductors 9, 9. Each insert is 95 bent to form a spring 22, and thereby to make a sure contact with the plug 20.

I prefer the particular form of my invention illustrated in the drawing, which is constructed in the following manner, first by 95 moulding an insulating material, such as bakelite, hard rubber, porcelain or similar substance into a box 7, rectangular in cross section, having a cylindrical end recess, and a flange extending around the upper edge, 100 constituting a moulded unitary box of insulating material, open at the bottom and provided with longitudinal channels in the base for the conductors 9, 9, and vertical openings for the inserts 10, 10 and 16. The 105 conductors 9, 9, with the inserts 10, 10 and 16 are then introduced through the open bottom of the box into the positions respectively provided for them. The bottom is 110 then filled and tightly sealed by a suitable

insulating material in which the conductors 9, 9 and their connections are permanently embedded.

The box is also adapted to be closed after 5 the conductors 9, 9 are inserted and connected with the inserts 10 and 16 by securing a solid flat bottom of insulating material thereto by screws or other fastening means without imbedding the conductors 9, 10 9 in insulating material. This is an important feature of my invention. It provides a box or shell that not only may be used for such sized conductors as the manufacturer may select, but the conductors and their 15 connections are readily accessible for alterations or repairs or removable for the purpose of substituting new conductors and other parts.

It is evident that my receptacle is also 20 adapted for use in the wall of a dwelling house. It may be set into a recess made for it in the wall, the plate 8 being left flush with the surface of the wall, and used to take the current to any desired electric fix-

ture in the room. In such event the current 25 would be taken from the house wires in any ordinary way in the rear of the box, thereby dispensing with the cylindrical recess 11, and the inserts 16 therein in the face of the plate 8.

What I claim and desire to secure by Letters Patent is:

An electrical receptacle consisting of a moulded unitary structure composed of insulating material having a longitudinal recess formed in the base thereof, and a pair of longitudinal channels opening into said recess, a plurality of pairs of outlets through said structure opening into said channels from the top and perpendicular thereto, a 40 pair of conductors loosely contained and supported in said channels, contacts in said outlets for connecting attachment plugs with said conductors and a closure member of insulating material in said recess.

In testimony whereof I have hereunto set my hand this 23d day of January, 1924.

WILLIAM H. NICHOLS.
